(57) **CLAIM**

The ornamental design for a head for a golf club, as shown and described.

DESCRIPTION

FIG. 1 is a first perspective view of a head for a golf club showing my new design;

FIG. 2 is a second perspective view thereof;

FIG. 3 is a front view thereof;

FIG. 4 is a left side view thereof;

FIG. 5 is a right side view thereof; and,

FIG. 6 is a top view thereof.

The part of the drawings shown in broken lines illustrates a portion of the head for a golf club that forms no part of the claimed design.
